tion of Pennsylvania

Application July 14, 1948, Serial No. 38,728.

14 Claims. (Cl. 105—399)

1

The invention relates to the construction of bodies for land vehicles of long prismatic shape and comprising underframe, roof and side wall structures. This is the type of body used outstandingly for railway cars of passenger trains, but also used, although in shorter length, for freight cars and highway busses, trucks and trailers.

More specifically, the invention relates to bodies of the indicated type having an outer roof skin of thin gauge sheet metal, which may be corrugated longitudinally, and having a gently arched mid portion of the roof adjoined by more strongly arched side portions, the latter merging into the side walls.

An outstanding object of the invention is the preventing or minimizing of the formation of transverse waves or buckles in the roof skin which occur outstandingly in the flat or slightly arched top region of the thin gauge roof skin. Such waves or buckles of the roof skin, tending to mar the appearance of the otherwise smooth and straight lines of an immaculate modern railway car, are observed most frequently on hot days when a car is exposed to strong overhead sunlight. The causes of such waves remained obscure for a long time, thereby barring the discovery of effective countermeasures.

The present invention is based on the novel concept that differential heating of the roof skin, on the one hand, and of other body parts, on the other hand, causes the more highly heated portions of the roof skin, which have little resistance against bending or buckling, to expand while such expansion is restrained by the other less heated and consequently less expanded parts, thereby forcing the skin to wave or buckle, and the invention remedies this situation by holding the roof skin, preferably only its approximately horizontal mid portion, in longitudinal tension. A roof skin tensioned in this manner can not buckle on account of differential heating unless and until the thermal expansion differential surpasses the previous lengthening of the roof skin due to the tension imparted thereto.

The invention also relates to a method of assembling a body of the indicated type. Broadly speaking, this method consists in assembling the body so that the middle portion of the roof skin is tensioned while other elements are compressed. A specific form of this method involves preassembling roof and side walls so that their mating edges diverge vertically toward the ends of the body and require bending the roof in final assembly to make its margins conform to the side wall

2

margins, thereby imparting tension to the roof top.

The above outlined and further objects, advantages, features and the details of the invention will be more fully and more easily understood from the embodiments of the invention illustrated in the attached drawings and described in the following:

In the drawings,

10 Figure 1 is an exploded side elevation of a railway car body comprising a preassembled roof unit and a unit including the side walls, end walls and underframe prior to the final assembly of these units into the completed body structure;

15 Figure 2 is a side elevation of the body after the units as shown in Figure 1 have been finally assembled with each other;

20 Figure 3 is a diagrammatic section through the body along line 3—3 of and on a larger scale than Figure 2;

25 Figure 4 is a larger-scale fragmentary perspective inside view of adjoining portions of the roof unit and one of the side wall units after their final assembly;

30 Figure 5 is a perspective view of the side wall portion shown in Figure 4 prior to its final assembly with the roof unit;

Figure 6 is an exploded side elevation similar to but more diagrammatic and on a smaller scale than Figure 1, illustrating a modified method of assembling the body in accordance with the invention;

35 Figure 7 is a fragmentary sectional perspective view of a roof unit with a smooth skin which is outstandingly susceptible to waves and calls for using the invention;

Figure 8 is a fragmentary sectional perspective view of one of the side walls to be united with the roof shown in Figure 7; and

40 Figure 9 is a diagrammatic longitudinal section through part of the roof shown in Figure 7.

Following a customary procedure, the railway car body illustrated in Figures 1 through 5 is built up of the following preassembled units: an underframe unit U, two side wall units S, a vestibule and a non-vestibule end wall unit V and NV, the former combined with end door posts P, and a roof unit R. The underframe unit U and the end wall units V and NV are merely diagrammatically indicated in the drawing because their construction may be of known design. The underframe unit may be preassembled with the side wall units S, the posts P and sometimes the end wall units V and NV into a larger unit to which the roof unit R is then added in final assembly.

Each side wall unit S comprises a plurality of longitudinally spaced vertical posts 10 interconnected by a bottom sill or chord 11, a window sill or chord 12, a window header or chord 13, dead light panels 14 between the window openings, and a shear panel 15 between bottom sill 11 and window sill 12. The upper ends of the posts 10 of the side wall unit prior to their assembly to the roof project freely beyond the window header 13 and are provided on the inside with gusset plates 16 constituting part of the final assembly means between the side wall unit and the roof unit. The end regions of each side wall unit are reinforced by vertically reinforced shear panels 17.

The underframe structure U comprises a transversely reinforced shear panel 18, side sills 19 connected in final assembly with the sills 11 of the side walls, and mostly comprises, in addition, a center sill, cross bearers and bolster beams which are not shown. The lines 20 indicate the location of the axis of the center plates on the bolster beams by which the body is carried on the trucks, likewise not shown.

The roof unit R comprises a continuous upwardly facing channel-section sleeper or chord structure 21 on each side, longitudinally spaced Z-section carlines 22 having their ends secured in the sleepers 21, a longitudinally corrugated roof skin 23 secured to the outer arms of the carlines 22, and on each side a downward extension of the roof skin, which may be in the form of a flat letterboard 24, and the lower margin of which is reinforced by a molding 25. The roof is further reinforced by longitudinal purflines 26 secured to the carlines 22 and to the adjoining portions of the roof sheathing 23. The lateral edge portions 27 of the roof are strongly arched and these portions merge without abrupt change of direction into the side walls and into 40 the nearly horizontal, gently arched middle portion 28 of the roof.

As indicated in the drawings, the elements entering into the structure consist of sheet metal, preferably high tensile stainless steel, and are 45 secured together by spot or seam welding, resulting in an integral self-supporting body structure.

In final assembly, the roof unit R is slid telescopically over the side wall units S which, as 50 indicated before, previously may have been united with the underframe, end wall and post units U, V, NV and P, whereupon the gussets 16 on the posts 10 are secured by spot or plug welding to the inner wall of the roof chords 21, and the moldings 25 are secured to the outer flanges of posts 10 and window headers 13 of the side wall units.

The construction and the assembly procedure described so far are substantially identical with 55 the disclosure in applicant's Patent No. 2,514,123, July 4, 1950. Certain features are also shown in the application Serial No. 38,726 of Gladeon M. Barnes, Charles L. Fike and the present inventor, entitled "Roof for Land Vehicles, Especially Railway Cars, and Method of Making the Same", filed July 14, 1948, simultaneously with the present application.

The previously mentioned waviness of the roof skin or sheathing develops outstandingly in the 70 approximately horizontal, gently arched mid region 28 and, more specifically, in about the central third of the length of the body. The occurrence of the waves or buckles in this restricted region is believed attributable to the combined

influences of the above described differential thermal expansion and the compression of the roof due to the deformation of the body under the load supported by it, such deformation obviously being greatest halfway between the supports of the body at 20. The lateral regions 27 of the roof sheathing are less apt to become wavy because of the stiffness derived from their arched cross-section and on account of the fact that they are less exposed to continuous overhead sunlight.

The invention reduces or suppresses the susceptibility to waves of the roof sheathing in the generally horizontal mid-roof region 28 by pretensioning the roof sheathing in this region, or at least the portion thereof near and adjacent the longitudinal center of the body. The extent of the region which is so pre-tensioned may be varied to fit the specific construction of the car body to which it is applied and the experience gained in regard to the limits of the region in which waviness may occur. Obviously, the desired result is achieved if the pretensioning is applied to a region larger than actually required.

One method of imparting the tensioning of the roof sheathing, which is illustrated in Figures 1 and 2, consists mainly in preassembling the side wall units or the side wall units with the underframe unit on the one hand, and the roof unit on the other hand, with different camber so that when the roof is superimposed on the side walls the mating margins of both types of units diverge from the longitudinal center toward the ends of the body.

As illustrated in Figure 1, the roof unit is assembled with the camber zero, that is: assembled with no camber at all, whereas the side wall units, with or without the underframe unit, are assembled so that the longitudinal mid region is higher than the end regions. The dot-and-dash line 29 is a straight horizontal line parallel to the lower margins of the roof and showing the pronounced camber of the side wall units. Actually, the camber of the side wall units need not extend over the entire length of the car, but only over the mid portion thereof, such as over the portion between the supports at 20, whereas the outward regions may be straight. As will become apparent later on, this latter feature is in line with the above explained restriction of the occurrence of waves to the longitudinal mid region of the car.

In building the car, the following sequence of assembly operations is preferred: the roof and the side frames or walls are built to the desired camber in separate jigs; the side frames are then assembled with underframe and end walls on supports maintaining the camber; the roof unit is applied to the assembly consisting of side, ends and underframe, which assembly is still supported in maintaining the camber.

For finally connecting the roof unit U with the side walls S, the two are forced into continuous engagement with each other along their meeting margins, which means that the roof has to be bent down at the ends and/or the ends of the side walls have to be bent up. Such bending is well within the elastic limits of these structures. Whichever bending procedure is followed, after the roof is structurally united with the side walls and the body freed of the assembly fixtures or jigs, the roof ends will be held by the side walls in the downwardly bent form, causing the top portion of the roof to be held under tension, whereas a certain amount of compression

will be imparted to the downwardly projecting portions of the roof. The roof unit represents a downwardly facing channel-section girder or beam having a horizontal neutral plane above and below which the longitudinal members of the roof are held under tension and compression respectively. The neutral plane in this construction is located above the bottom level of the sleepers approximately one-third the distance between said level and the apex of the roof.

The tension under which the roof sheathing in the region 28 is held will effectively prevent the waviness of the sheathing which otherwise might be caused by thermal expansion alone or in combination with the downward bending of the entire body due to the load carried between its supports 20.

The embodiment diagrammatically illustrated in Figure 6 differs from the first embodiment in that the side walls S', with or without under-frame U', end walls NV', V' and posts P', are assembled without camber, as indicated by the dot-and-dash line 30 representing the top margin of the side walls. The roof unit R', on the other hand, is assembled so that its mid portion is lower than the end portions. The amount of the camber is revealed by comparison of the roof with the straight horizontal dot-and-dash line 31. The result of forcing the mating margins of said wall units S' and roof unit R' into engagement with each other is substantially the same as that obtained by the construction and procedure according to Figures 1 and 2.

For the tensioning of the roof skin by the differential-camber method, it is apparently only essential to assemble roof and side walls so that their meeting margins diverge from the longitudinal mid region of the body toward the ends thereof, and it is not essential which of the two types of units has its margins curved or cambered, or whether the margins of both types of units are curved to a different degree. Nor is it necessary that the entire respective unit or units have the camber. For practical reasons, however, it appears recommendable to impart a camber at least to the side wall units because such camber is also, for other reasons, customarily imparted to railway car bodies.

It is also considered desirable to select the conditions so that the completed body structure retains a specified amount of camber which will be straightened out under the load of the equipment attached to the mid portion of the car. This, too, is in line with customary practice.

From these explanations, it follows that the embodiment illustrated in Figure 6 represents an extreme case which, although unlikely to be adopted in practice, will clarify the extent to which the method per Figures 1 and 2 may be modified.

For a railway car of the construction illustrated in Figures 1 to 6, a difference of camber between the mating margins of the side walls and roof amounting to $\frac{3}{4}$ " for a distance of 59' 6" between the supports at 20, is considered adequate. For a total length of the same body of about 85', this involves a total difference of camber of approximately 1.5". In the drawings, the amount of the camber is exaggerated. The full understanding of the invention may be facilitated by giving some further dimensions of parts which influence the result. As examples, the following are dimensions designed to be used in the body illustrated in Figures 1 to 5 or in Figure 6: gauge of the roof skin .02"; radius of transverse

curvature of the marginal portions 27 of the roof skin, about 20"; radius of transverse curvature of the central portion 28 of roof skin, about 10' to 11'; gauge of roof sleepers and carlines .06"; spacing of carlines, about 27.5"; width of body, about 10'; gauge of letterboard .09"; and height of side walls, about 7.5'.

The invention is, perhaps with even greater benefit, applicable to constructions having a smooth roof skin which is more subject to waviness than a skin stiffened to some extent by corrugations. Furthermore, the invention is not restricted to a roof unit comprising a skirt or letterboard which extends downwardly beyond the lateral roof chords. A construction in which the roof skin terminates at the lateral chords is more easily bendable than a roof having downwardly depending skirts or letterboards to be held in compression which, unless special precautions are taken, might lead to waviness of these skirts.

A construction having a smooth roof surface and the letterboards on the side walls is illustrated in Figures 7 to 9. The roof sheathing or skin is composed of transverse strips 32 which may be formed of coil stock approximately 27" wide and having one edge joggled at 33. In a special fixture, each of these sheets 32 is welded at wide intervals by its joggled margin 33 to one of the carlines 34, resulting in subassemblies, each consisting of one sheet and one carline, which are then placed progressively in the sleeper channels 35 so that each unit may be welded to the previously installed units by means of a reasonably short-throated tool or multiple-electrode special set-up reaching in through the end. In addition, two purlines (not shown) may be used at the same location as that illustrated in Figure 3, and possibly a further purline along the center line, indicated by the dot-and-dash line 36 in Figure 9. The sleepers and the purlines may be welded to each subassembly unit as it is installed, thereby completing the roof unit R'.

Each side wall unit S' includes vertical posts 37 which are interconnected by dead light panels 38 and by chord structures and sills (not shown) in a manner similar to that shown for the construction of Figures 1 to 5. However, the side wall units of this embodiment differ from the first embodiment in that they include the letterboard 39 and the header molding 40. The letterboard may have a gauge of .09" and the roof sheets a gauge of .05" to .06". The material of both these elements and of most of the other elements entering into the construction is preferably high tensile material, for instance, cold rolled austenitic stainless steel.

In order to help keep the roof skin flat in the car, the top portion of the skin is held in tension. Similarly to the procedure described for the previous embodiments, the roof may be built to less camber than the car, and possibly even reverse camber. When the roof is pulled to the camber of the side frames in the final assembly, the roof is bent about its horizontal neutral plane, and this will tend to stretch the sheets tight in the upper portion where curvature is least and buckles are most likely to occur. In this construction, the neutral plane is located above the bottom level of the sleepers at approximately $\frac{1}{6}$ the distance between said level and the apex of the roof.

The connection between roof and side walls may be strengthened by a web 41, indicated by dot-and-dash lines in Figure 8, which is secured

to the posts 31, and sleepers 35 and the carlines 34.

In addition to the illustrated and described embodiments, the invention is susceptible to many further modifications and to adaptations to different body constructions. It is important to understand that the procedures for tensioning the roof skin illustrated and described in this application may be modified or replaced by other procedures which, in the knowledge of the condition to be imparted to the roof skin in accordance with the invention, present themselves to those skilled in the art. In short, protection is sought for the broad aspects of the invention in addition to protection for combinations including specific features of the body construction and independently of any specific methods by which the inventive condition of the roof skin is attained.

What is claimed is:

1. In a railway car body for passenger trains, comprising side walls and a transversely arched roof, the roof including longitudinally spaced transverse carlines secured at their ends to the side walls and a thin roof sheathing secured to the carlines, the marginal portions of the roof and the side walls presenting vertically disposed beams of appreciable extent and bending moment, said roof sheathing at least in part being held under longitudinal tension by said marginal portions and side walls so as to avoid waviness of the roof sheathing especially when exposed to strong overhead sunlight causing thermal expansion of the sheathing.

2. In a railway car body for passenger trains in the form of a long prismatic body having a transversely arched roof, the body including longitudinally extending frame structures of considerable vertical extent adapted to withstand compression loads without buckling and a roof skin of thin sheet metal supported by and secured to longitudinally spaced transverse carlines, the approximately horizontal mid region of the roof skin being held under tension by said longitudinal frame structures to counteract the tendency to the formation of waves and buckles in said mid region of the roof skin.

3. In a terrestrial closed vehicle body of elongated prismatic form, such as a railway car body for passenger trains, having longitudinally extending side walls and a transversely arched roof; said side walls having greater resistance against bending in vertical direction than the roof; said roof comprising lateral longitudinally extending chord structures, longitudinally spaced transversely extending carlines secured by their ends to said chord structures, and a sheet metal roof sheathing secured to the outside of said chord structures and carlines; the marginal portions of the roof and the side walls presenting vertically disposed beams of appreciable extent and bending moment; the gauge of said roof sheathing being so small as to render it susceptible to the formation of waves, especially when exposed to strong overhead sunlight; in the completed body, said roof structure being held in a condition in which its ends are bent downwardly by said side walls thereby imparting tension to the mid region of the roof skin between its lateral sides and counteracting the susceptibility to the formation of waves.

4. In a terrestrial closed vehicle body of elongated prismatic form, such as a railway car body for passenger trains, having longitudinally ex-

tending side walls merging without abrupt change of direction into the sides of a transversely arched roof; said side walls having great resistance against compression in longitudinal direction and against bending in vertical direction; said roof comprising lateral longitudinally extending chord structures, longitudinally spaced transversely extending carlines secured by their ends to said chord structures, and a roof sheathing of longitudinally corrugated sheet metal secured to the outside of said chord structures and carlines; the gauge of the roof sheathing being so small as to render it susceptible to the formation of waves; in the completed car body said roof structure being held in a state in which its ends are bent downwardly thereby imparting tension to the mid region of the roof skin between its lateral sides and counteracting said susceptibility to the formation of waves.

20 5. In a terrestrial closed vehicle body of elongated prismatic form, such as a railway car body for passenger trains, having longitudinally extending side walls interconnected at the top by a roof, said roof having arched side portions merging without abrupt change of curvature into the side walls and into the less arched approximately horizontal mid portion of the roof, said roof comprising an outer sheathing of longitudinally corrugated thin sheet metal; the marginal portions of the roof and the side walls presenting vertically disposed beams of appreciable extent and bending moment; said sheathing in said approximately horizontal mid portion of the roof being held under tension in longitudinal direction by its connection to said side walls so as to counteract the tendency to formation of waves in this region of the roof.

6. In a closed land vehicle body forming an elongated prismatic hollow beam of the type used for railway cars, busses, trucks and trailers, and having side walls, strongly arched portions along the upper longitudinal margins of the body merging into the side walls and into a gently curved portion of the roof interconnecting said strongly arched corner portions, said gently curved roof portion having a thin gauge sheet metal skin held, at least in the longitudinal mid section of the body, under longitudinal tension by adjoining longitudinally extending elements of the body.

7. In a closed land vehicle body of elongated prismatic form of the type used for railway cars, busses, trucks and trailers, having side walls and a transversely arched roof merging by its lateral portions into the side walls without abrupt change of direction, longitudinally extending sleepers in the regions where roof and side walls meet, longitudinally spaced transverse carlines interconnecting the sleepers and a thin gauge roof sheathing secured to the outside of the carlines, the body including a roof unit preassembled independently of the preassembled side walls, the side walls and the roof unit being preassembled so that prior to the connection between side walls and roof unit their mating margins diverge vertically in longitudinal direction from the longitudinal mid region of the body toward the end regions, the top portion of the roof sheathing being in the state of tension in the finished body due to the forcing together of the diverging margins of side walls and roof and the ensuing bending of the roof.

8. In a closed land vehicle body of elongated prismatic form of the type used for railway cars,

busses, trucks and trailers, having side walls and a transversely arched roof, the latter merging by its lateral portions into the side walls without abrupt change of direction, longitudinally extending sleepers in the regions where roof and side walls meet, longitudinally spaced transverse carlines interconnecting the sleepers and a thin gauge roof sheathing secured to the outside of the carlines, the marginal portions of the roof and the side walls presenting vertically disposed beams of appreciable extent and bending moment, the body being assembled so that the roof is held in a condition in which portions thereof remote from the longitudinal middle of the body are held in downwardly bent state, thereby holding the top portion of the roof sheathing in tension.

9. In a transversely arched roof for land vehicle bodies, especially railway car bodies of passenger trains, longitudinally extending structural members adapted to withstand compression loads without buckling, and a roof skin of thin sheet metal supported by and secured to longitudinally spaced transverse carlines, the longitudinal mid region only of the roof skin being held under tension by compression of said longitudinal structural members.

10. In a method of building elongated prismatic land vehicle bodies of the type used for passenger railway trains and having a transversely arched roof with a thin roof sheathing, compressing longitudinal structural members of the body near the top thereof while assembling the body, and letting such compression react against the sheathing at the top of the roof so that this part of the sheathing is tensioned for straightening it and for preventing the formation of waves and buckles therein due to heat expansion and other causes.

11. In a method of building elongated prismatic land vehicle bodies of the type used for passenger railway trains and having a thin roof sheathing, the step of preassembling a roof unit independently of the side walls so that the top margins of the side walls and the mating lateral margins of the roof unit differ in camber and diverge toward the ends of the body, and the step of securing the mating margins of side walls and roof unit together while bending the ends of the roof downwardly, whereby the roof sheathing above the neutral plane of the roof unit is tensioned so as to prevent the formation of waves in the roof sheathing due to heat expansion and other causes.

12. In a method of building elongated prismatic land vehicle bodies of the type used for passenger railway trains and having a thin roof sheathing, the step of preassembling a roof unit independently of the side walls so that the top margins of the side walls and the mating lateral

margins of the roof unit differ in camber and diverge toward the ends of the body, the step of preassembling the side walls with the underframe into one unit prior to the assembly of this combined unit with the roof unit, and the step of securing the mating margins of side walls and roof unit together in bending the ends of the roof downwardly, whereby the roof sheathing above the neutral plane of the roof unit is tensioned so as to prevent the formation of waves in the roof sheathing due to heat expansion and other causes.

13. In a method of building elongated prismatic land vehicle bodies of the type used for passenger railway trains and having a transversely arched roof with a structural sheet metal skin, the step of independently preassembling side wall units and a roof unit so that the side wall units and the roof unit differ in camber and, 15 when superimposed preparatory to their connection, have their mating margins diverging from the middle toward the ends of the body, and the step of securing the mating margins of side wall units and roof unit together while bending the 20 ends of the roof downwardly and causing the roof sheathing above the neutral plane of the roof structure to be tensioned.

14. In a method of building elongated prismatic land vehicle bodies of the type used for passenger railway trains and having a transversely arched roof with a structural sheet metal skin, the step of independently preassembling side wall units and a roof unit so that the side wall units and the roof unit differ in camber and, 30 when superimposed preparatory to their connection, have their mating margins diverging from the middle toward the ends of the body, the step of connecting the side wall units, prior to their assembly with the roof unit, with a preassembled underframe unit while maintaining the camber, and the step of securing the mating margins of side wall units and roof unit together while bending the ends of the roof downwardly and causing the roof sheathing above the neutral plane of the 35 roof structure to be tensioned.
